per Thos. S. Crane, Atty

UNITED STATES PATENT OFFICE.

PERCY S. MARCELLUS, OF ORANGE, NEW JERSEY.

DESIGN FOR A TOOTHBRUSH.

58,445.

Specification for Design.

Patented July 19, 1921.

Application filed May 19, 1920. Serial No. 382,602. Term of patent 14 years.

To all whom it may concern:

Be it known that I, PERCY S. MARCELLUS, a citizen of the United States, residing at 23 Lincoln Place, Orange, county of Essex, and State of New Jersey, have invented a new, original, and ornamental Design for a Toothbrush, fully described and represented in the following specification and the accompanying drawings, forming a part of the same.

The drawing Figure 1 shows a plan view, Fig. 2 a side view, and Fig. 3 an end view of a toothbrush showing my new design for the handle.

Fig. 1 shows that the handle is bent laterally from the head of the toothbrush at an angle of about 45 degrees.

Fig. 2 shows that the handle is also bent upwardly from the plane of the head of the toothbrush; and Fig. 3 shows that the handle is bent both sidewardly and upwardly, as shown in the plan and side view.

The drawing will be clearly understood by reference to the model which accompanies this application.

I claim:

The ornamental design for a toothbrush, as shown.

In testimony whereof I have hereunto set my hand.

PERCY S. MARCELLUS.
